UNITED STATES PATENT OFFICE

139,031

DESIGN FOR A RADIO CABINET OR SIMILAR ARTICLE

Louis L. Von Cseh, East Cleveland, Ohio, assignor to Meters & Pumps, Inc., Cleveland, Ohio, a corporation of Ohio

Application May 3, 1944, Serial No. 113,450

Term of patent 7 years

(Cl. D56—4)

To all whom it may concern:

Be it known that I, Louis L. Von Cseh, a citizen of the United States, residing at East Cleveland, in the county of Cuyahoga and State of Ohio, have invented a new, original, and ornamental Design for a Radio Cabinet or Similar Article, of which the following is a specification, reference being had to the accompanying drawing, forming part thereof, wherein Fig. 1 is a front elevational view and Fig. 2 a side elevational view of a radio cabinet showing my new design, it being noted that the base and molding of the

rear portion of the cabinet is the same as illustrated in Fig. 1 and the remaining part of such rear portion is a plain flat surface, it being noted further that the other side of the cabinet shown in Fig. 2 is the same as that shown in said figure. The dominant features of the design reside in the portions illustrated in full lines.

I claim:

The ornamental design for a radio cabinet or similar article, as shown and described.

LOUIS L. VON CSEH.
